UNITED STATES PATENT OFFICE.

WILLIAM H. MINER, OF CHICAGO, ILLINOIS.

RAILWAY DRAFT-RIGGING.

1,136,029.

Specification of Letters Patent.

Patented Apr. 20, 1915.

Application filed March 9, 1914. Serial No. 823,491.

To all whom it may concern:

Be it known that I, WILLIAM H. MINER, a citizen of the United States, residing at Chicago, in the county of Cook and State of Illinois, have invented a certain new and useful Improvement in Railway Draft-Rigging, of which the following is a full, clear, concise, and exact description, reference being had to the accompanying drawings, forming a part of this specification.

My invention relates to improvements in draft rigging for railway cars.

The object of my invention is to provide a draft rigging of efficient operation and one adapted to afford an easy start to the railway cars to which the same is applied.

In the drawings forming a part of this specification, Figure 1 is a plan view, partly in horizontal section, of a draft rigging embodying my invention; Fig. 2 is a cross-section on line 2—2 of Fig. 1; Fig. 3 is a cross-section on line 3—3 of Fig. 1; Fig. 4 a side elevation of the draft gear; Fig. 5 a perspective view of the draft gear shell; and Fig. 6 a perspective view of the rear follower.

Referring to the drawings, the numerals 7—7 indicate draft sills or parts of the car-frame to which the draft rigging is applied; 30 8—8 front stop-members having the front stop-shoulders 9—9; 10—10 rear stop-members having the rear stop-shoulders 11—11.

The numeral 12 indicates the draw-bar, the rear end of which only is shown in Fig. 35 1 of the drawings, to which is secured the draft yoke 13 inclosing the front follower 14 and the draft gear 15.

The parts are supported between the sills by the tie-plate 16 suitably secured to the draft members 7—7 by the bolts 17—17.

The draft gear 15 comprises a shell 18 having a pair of forwardly opening chambers 19—19 in horizontal twin arrangement therein. Each of said chambers is closed at its rear end by a preferably integral plate 20, and rearwardly thereof the shell is provided with the rearwardly opening preliminary spring chambers 21—21. The forwardly opening chambers 19 are provided 45 with the internal friction faces 22—22, and each contains the friction elements 23 comprising the wedge 24 and the friction shoes 25—25 and the spring elements 26, preferably consisting of an outer spring 27 and 50 an inner spring 28, the said springs being forwardly seated against the friction ele-

ments, and rearwardly seated against the plate 20. A connecting rod 270 engages the friction elements at one end and a plate 20 at the other end. In each of the preliminary spring chambers 21 is mounted the preliminary spring members 29, each comprising preferably an outer spring 30 and an inner spring 31, the said springs being forwardly seated against the plate 20, and 55 rearwardly seated against the rear follower 32 and about the bosses 33 with which the inner face of the rear follower is provided.

The rear follower 32 comprises a plate 34 of sufficient dimensions to close the rear ends 70 of the preliminary spring chambers 21—21, and having a forwardly extended collar 35 adapted to surround said preliminary spring chambers and to engage the shoulder 36 with which the rear end of the shell is provided to limit its forward movement in relation to the shell 18. The collar 35 is provided above and below the shell 18 with the forwardly extended wings 38—38, the said wings in preferable construction being conformed to the adjoining portions of the shell 18, which in preferable construction is provided above and below with the medium grooves 39 within which the wings 38 are adapted to reciprocate. The said wings 38 are each provided with a slot 40 adapted to register with a slot 41 vertically extended through the shell 18 and between the chambers thereof. The said slots in the follower and shell are adapted to receive a vertical key 42 terminating at its ends within the space between the limbs of the yoke 13. In preferable construction the friction elements and spring elements within the chambers 19 are of greater compression resisting capacity than the preliminary springs in the preliminary spring chambers of the shell.

In assembling the parts of the draft gear, the preliminary springs are placed in their appropriate spring chambers and are of a suitable length so that in assembling the rear follower with the other parts of the draft gear the preliminary springs are placed under an initial compression before the slots 105 in the wings 38 of the follower register with the slot 41 through the shell. The placing of the key through the said slots holds the preliminary springs under an initial compression. The slots 40—40 in the wings 38 110 of the rear follower are suitably rearwardly extended to permit forward movement of

the rear follower in relation to the shell 18. On forward movement of the draw-bar, the rear follower is drawn forwardly by means of the yoke 13 compressing the preliminary 5 springs within the preliminary spring chambers until the rear follower engages the shoulder 36 upon the shell 18. Thereupon, on further forward movement of the draw-bar the friction and spring elements in the 10 chambers 19 act in the usual manner, which is well understood. On rearward movement of the draw-bar the rear follower is stopped by the rear stop-shoulder 11—11, and the preliminary springs are compressed until 15 the rear follower engages the shoulder 36 of the shell, whereupon the action of the parts within the chambers 19—19 continues in the usual well known manner.

It will thus be apparent that in my device 20 the very high capacitated friction and spring elements in the chambers 19 may be employed, and that by reason of the preliminary springs an easy initial movement of the compression resisting member is insured.

25 I claim:

1. In a draft rigging for railway cars, the combination with draft-members, stop-members and draw-bar, of a shell, friction elements and spring elements within the shell, 30 a rear follower, a key and preliminary springs between the shell and rear follower, the key slidably engaging the rear follower to the shell.

2. In a draft rigging for railway cars, the 35 combination with draft-members, stop-members and draw-bar, of a shell, friction ele-

ments and spring elements within the shell, a rear follower, a key and preliminary springs between the shell and rear follower, the key passing through the shell and rear 40 follower to hold the preliminary springs under initial compression.

3. In a draft rigging for railway cars, the combination with draft-members, stop-members, draw-bar and yoke, of a shell having 45 forwardly opening chambers in horizontal twin arrangement, a rear follower, preliminary springs between the shell and rear follower, and a key, each chamber of the shell containing friction elements and spring elements, the follower being provided with forwardly extending wings slidably connected to the shell by means of the key.

4. In a draft gear for railway cars, a shell, forwardly opening chambers in said 55 shell in twin arrangement, compression resisting elements in each of said chambers, rearwardly opening chambers in said shell, preliminary springs in each of said chambers, a follower and a key, the follower being provided with forwardly extending wings the shell being provided with grooves in which said wings are adapted to reciprocate, the key passing through the shell 60 and slidably engaging the follower, the 65 preliminary springs being seated against the follower and being held under initial compression by the key and follower.

WILLIAM H. MINER.
